GREASE GUN

Eugene J. Macey, Rosholt, S. Dak.

Application January 30, 1933. Serial No. 654,345

6 Claims. (Cl. 221—47.3)

This invention relates to an improved grease gun and seeks, among other objects, to provide a device of this character wherein a pivoted hand lever will be provided for actuating the grease 5 ejecting plunger employed.

A further object of the invention is to provide a device wherein the plunger will be housed within a barrel and will not reciprocate through the grease within the grease receptacle of the device.

And the invention seeks, as a still further object, to provide a device wherein the barrel, plunger and associated parts, will be readily removable with the cap of the grease receptacle so 15 that said receptacle may be readily filled with grease.

Other and incidental objects of the invention, not specifically mentioned in the foregoing, will be apparent during the course of the following 20 description.

In the accompanying drawing, Figure 1 is a vertical sectional view through my improved gun, a discharge hose and lubricator fitting being shown in elevation, and

25 Figure 2 is a plan view of the device.

In carrying the invention into effect, I employ a preferably cylindrical grease receptacle 10 contracted at its lower end portion to provide a reduced terminal 11 on which is formed an inwardly directed annular flange 12 and screwed over the upper end of the receptacle is a removable cap 13.

Extending at its upper end through the cap is an axially disposed barrel 14 upon which is 35 screwed nuts 15 abutting the inner and outer sides of the cap for rigidly connecting the barrel thereto. The barrel is of a diameter to fit snugly within the terminal 11 of the receptacle 10 and is formed at its lower end with a reduced nipple 16 40 which extends snugly through the flange 12. At the upper end portion of the barrel, the bore 17 thereof is enlarged to provide a chamber 18, while, at the lower end portion of the barrel, the bore thereof is reduced, and formed through the side 45 wall of the barrel, near the lower end thereof, is an inlet passage 19 communicating with a grease chamber 20 provided by the reduced lower end portion of the bore of the barrel.

Slidable in the barrel is a plunger 21 having 50 a reduced lower end portion 22 fitting the reduced lower end portion of the bore 17 of the barrel and formed on the plunger, at its upper end, is a yoke 23 through the sides of which extends a transverse pin 24. Freely accommodated at one end within the chamber 18 of the

barrel 14 is a spring 25 which surrounds the upper end of the plunger and rests at its opposite end against the yoke 23. Thus, as will be seen, this spring will function to retract the plunger and will normally hold the plunger in retracted position when, as will be observed, the lower end of the plunger will be disposed immediately above the inlet passage 19 of the grease chamber 20. Slidable on the barrel is a grease follower including a sleeve 26 fitting the barrel and mounted on 60 the sleeve is a pair of spaced plates 27 between which is clamped a leather 28, the free margin of which is disposed to coact with the wall of the receptacle 10.

Mounted upon the cap 13 is a handle 29 which 70 extends diametrically of the cap thereabove. At its forward end portion, the handle is inclined forwardly and downwardly to meet the cap to which the forward extremity of the handle is suitably fixed at one side of the cap, and integral 75 with the sides of the handle are spaced posts 30 suitably secured to the cap at its opposite side. The handle is thus rigidly fixed to the cap and formed in the handle, as particularly seen in Fig. 2, is an elongated opening 31 freely accommodating the upper end of the plunger 21 therethrough. Pivoted between the posts 30 is a lever 32 which extends beneath the handle 29 and is provided at its forward end with an arcuate terminal 33 extending freely between the sides of 85 the yoke 23 at the upper end of the plunger, the concave face of said terminal being presented downwardly to coact with the yoke and the convex face of the terminal being presented upwardly to the pin 24. Thus, when the lever 32 is 90 rocked towards the handle 29, the plunger will be depressed while, when the lever is released, the plunger will be retracted by the spring 25.

Screwed over the terminal 11 of the grease 95 receptacle 10 is a removable coupling 34 stepped to fit the nipple 16 of the barrel 14, and disposed within said coupling to coact with the mouth of the nipple is a check valve 35 normally held closed by a spring 36. In the present instance, I have shown the coupling 34 as attached to a flexible discharge hose 37 which is equipped at its free end with a lubricator fitting, indicated as a whole at 39, this fitting being the subject of my co-pending application filed November 21, 1932, Serial Number 643,753. If preferred, however, the fitting 39 or other appropriate fitting adapted for detachable connection to a companion fitting upon a part to be lubricated may be attached directly to the terminal 11 of the grease 100 105 110

receptacle, in which event, suitable provision will be made for the check valve 35 and spring 36.

In use, the cap 13 is disconnected from the receptacle 10 when, by lifting on the cap, the barrel 14 is withdrawn from the receptacle. The receptacle may then be easily filled with grease, when the cap is replaced, care being taken to properly position the grease follower within the upper end of the receptacle. Having connected the fitting 39 with the part to be lubricated, the handle 29 is then grasped when, with the fingers, the lever 32 is swung upwardly for depressing the plunger 21. Downward movement of the plunger will, of course, serve to expel the contents of the chamber 20 past the check valve 35 and through the hose 37 and fitting 39 to the part to be lubricated. Upon release of the lever 32, the spring 25 will, as previously explained, immediately retract the plunger and as the plunger starts its upward movement the check valve 35 will close so that continued upward movement of the plunger will create, in the chamber 20, a partial vacuum which, when the plunger clears the passage 19 will be communicated to the grease receptacle. Accordingly, air pressure above the grease follower will act to force the follower downwardly and feed the grease through the passage 19 into the grease chamber 20 so that when the lever 32 is next swung upwardly, a fresh charge of grease will be expelled through the hose. Should the plunger stick, the lever 32 may be manually rocked when the convex face of the terminal 33 of the lever will coat with the pin 24 for positively retracting the plunger. I accordingly provide a device which will function efficiently until substantially all of the grease in the grease receptacle has been discharged therefrom.

Having thus described the invention, I claim:

1. A grease gun including a grease receptacle, a cap closing the receptacle, a barrel carried by the cap and provided at one end with a grease chamber and with an inlet passage connecting said chamber with the grease receptacle, a check valve coating with the mouth of said chamber, a plunger slidable in the barrel for expelling the contents of said chamber, and a lever carried by the cap and pivoted at a point between its ends to coat at one end with the plunger whereby the lever may be rocked for actuating the plunger.

2. A grease gun including a grease receptacle, a cap closing the receptacle, a barrel carried by the cap and provided at one end with a grease chamber and with an inlet passage connecting said chamber with the grease receptacle, a check valve coating with the mouth of said chamber, a plunger slidable in the barrel for expelling the contents of said chamber, a handle fixed to the cap, and a lever pivoted at a point between its ends upon the handle to coat at one end with the plunger whereby the lever may be rocked for actuating the plunger.

3. A grease gun including a grease receptacle,

a cap closing the receptacle, a barrel carried by the cap and provided at one end with a grease chamber and with an inlet passage connecting said chamber with the grease receptacle, a check valve coating with the mouth of said chamber, a plunger slidable in the barrel for expelling the contents of said chamber, a handle extending over the cap and fixed at one end thereto at one side of the cap, posts fixed to the cap at its opposite side and supporting the handle, said handle being provided with an opening freely accommodating the plunger, and a lever pivoted between said posts to coat with the plunger and operable for actuating the plunger.

4. A grease gun including a grease receptacle, a cap closing the receptacle, a barrel carried by the cap and provided at one end with a grease chamber and with an inlet passage connecting said chamber with the receptacle, a check valve coating with the mouth of said chamber, the opposite end of said barrel being formed with a recess, a plunger slidable in the barrel for expelling the contents of said chamber and provided at its outer end with a yoke, a spring disposed in the recess of the barrel and coating with said yoke for retracting the plunger, a handle carried by the cap, and a lever pivoted upon the handle to coat with said yoke and operable for actuating the plunger.

5. A grease gun including a grease receptacle, a cap closing the receptacle, a barrel carried by the cap and provided at one end with a grease chamber and with an inlet passage connecting said chamber with the receptacle, a check valve coating with the mouth of said chamber, the opposite end of said barrel being formed with a recess, a plunger slidable in the barrel for expelling the contents of said chamber and provided at its outer end with a yoke, a spring disposed in the recess of the barrel and coating with said yoke for retracting the plunger, a pin carried by the yoke, a handle carried by the cap, and a lever pivoted upon the handle and provided with an arcuate terminal having its concave face disposed to coat with the yoke for actuating the plunger when the lever is rocked and its convex face disposed to coat with said pin whereby the lever may be swung for manually retracting the plunger.

6. A grease gun including a grease receptacle, a cap normally closing the receptacle, a barrel carried by the cap and provided at one end with a grease chamber and with an inlet passage connecting said chamber with said receptacle, a check valve coating with the mouth of said chamber, a grease follower slidable upon the barrel to coat with the receptacle, a handle carried by the cap, a spring-retracted plunger slidably in the barrel for expelling the contents of said chamber, and a lever pivoted upon the handle to coat with the plunger for actuating said plunger.
